(57) **CLAIM**

The ornamental design for a motor-driven compressor, as shown and described above.

DESCRIPTION

FIG. 1 is a front view of a motor-driven compressor for a vehicle air conditioner, according to an embodiment of the design.

FIG. 2 is a rear view of the motor-driven compressor of FIG. 1.

FIG. 3 is a left side view of the motor-driven compressor of FIG. 1.

FIG. 4 is a right side view of the motor-driven compressor of FIG. 1.

FIG. 5 is a top view of the motor-driven compressor of FIG. 1.

FIG. 6 is a bottom view of the motor-driven compressor of FIG. 1; and,

FIG. 7 is a left side perspective view of the motor-driven compressor of FIG. 1.
